UNITED STATES PATENT OFFICE.

WILLIAM F. GATEWOOD, OF PIERCE CITY, MISSOURI, ASSIGNOR TO GEORGE L. MIDDLETON, OF VENICE, CALIFORNIA.

GATE.

1,379,094.

Specification of Letters Patent.

Patented May 24, 1921.

Application filed February 25, 1920. Serial No. 361,343.

To all whom it may concern:

Be it known that I, WILLIAM F. GATEWOOD, a citizen of the United States, residing at Pierce City, in the county of Lawrence 5 and State of Missouri, have invented new and useful Improvements in Gates, of which the following is a specification.

This invention relates to gates and particularly to means for holding a gate in closed position or in oppositely opened positions and to means for opening the closed gate in either of two directions and also for closing the gate in either of its opened positions; and has for its object to provide a 15 device that is simple, easily operable and inexpensive and that can be actuated from a remote point on opposite sides of the closed position line of the gate by a person driving toward the gate from opposite sides and 20 without having to leave the vehicle in which he or she may be; and a further object of the invention is to provide an apparatus for opening and closing a swinging gate all of the parts of which are readily accessible and 25 arranged above the surface of the ground so as to be inexpensively installed and repaired when necessary; and the invention consists of the construction and details an embodiment of which is illustrated in the 30 accompanying drawings and described and claimed herein.

Figure 1 is a perspective of the gate in its closed position with the actuating mechanism.

35 Fig. 2 is a perspective of the gate opened in one direction.

Fig. 3 is a plan view of the apparatus.

Fig. 4 is a side elevation of the apparatus partly in section.

40 Fig. 5 is a section on line 5-5 of Fig. 4.

Fig. 6 is a perspective of a fragment of the upper end of the latch post with retaining devices for holding the gate in closed position.

45 Fig. 7 is a perspective of the upper portion of one of the posts provided with a latch for retaining the gate in one of its open positions.

The gate obviously may be of any suitable 50 style or type of construction and of suitable material and comprises, in this illustration, a series of horizontal rails 2 with a set of upright stiles or retaining braces consisting of pairs of strip-like pieces 3 overlapping the interposed rail members 2. One end of the gate structure is provided with

suitable hinges 4-4 spaced in vertical position and shown as arranged on a hinge post 5 or other convenient support.

The opposite or swinging end of the gate 60 is designed in its closed position to stand in juxtaposition to a latch post 6, in this case, provided with a pair of upwardly yielding latch leaves 7 disposed in co-planar relation to swing upwardly on respective pivots 8, 65 the inner ends of the latches being provided with shoulders to rest upon a suitable support or ledge 9 that may be formed upon or attached to a plate 10 countersunk in the face of the latch post 6 although it is obvious that the latches 7-7 may be otherwise suitably mounted.

The lower ends of these latches are sufficiently spaced to provide a recess for the interposition of a bolt member 11 which, as 75 the gate swings on its hinges 4-4, slides across the lower inclined face 7^a of the latches 7 so that the latter are lifted severally according to the direction of movement of the gate, the opposed latch forming an 80 abutment at its lower front edge against which the bolt 11 will strike when it has come into proper position.

At a suitable distance from and alining with each other in a plane of the pivot or hinge post 5 is provided a set of latch posts 12, these being so disposed that when the gate 2 is opened in either direction on its hinges 4-4 the operative end of the bolt 11 will engage a retaining latch 13, such as is 90 clearly illustrated in Fig. 7, that is mounted on one or the other of the posts 12, as the case may be, and projecting so as to readily rise as the moving bolt 11 passes under its outwardly inclined end 13^a. Suitable stops 95 to limit the upward and downward movement of the latch 13 are shown as at 14.

While the bolt 11 may be operable in various ways to disconnect it from the retaining latches 7 or 13 it is here shown as 100 mounted intermediate its length on a pivot 15 mounted in the central stile or uprights 3 of the gate between which the bolt 11 is mounted. The bolt extends rearwardly or toward the hinged end of the gate and is 105 preferably provided with an overbalancing or weight portion 16 so that the outer end of the bolt is normally pressed upwardly to sweep into contact with the several latches according to the movement of the gate.

The bolt 11 is, in the present instance, designed to be rocked on its fulcrum or pivot

15 to lower its outer end from the engaged latch or latches, and this is accomplished by the use of a double acting device comprising a pair of downwardly extending rods 17 arranged on opposite sides of the rear end of the gate to be concurrently and oppositely reciprocated, the rods being guided through bearings 18 on opposite sides of the gate and having their lower ends inturned as at 19 5 toward each other to pass underneath of and engage the lower surface of the weighted end of the bolt 16. The upper ends of the rods are pivotally connected as at 20 to a small walking beam or lever 21 disposed 10 transversely across the top rail of the gate 15 and tiltable on a pivot 22 thereon. The upper ends of the rods 17 may be provided with hooks 23 forming the pivots, and in order to prevent the rods from working out of the 20 ends of the lever 21 suitable stop pins 24, Figs. 4 and 5, may be driven into the adjacent portion of the top rail of the gate.

To actuate the walking beam or lever 21 a lever 25 is turnable in a horizontal plane 25 about a vertical axis as the pivot screw 26 extends into a hub 27 that is clamped by the set screw 28 on the inserted rod or lever 25. The pivot screw 26 extends upwardly through a cap or bearing plate 29 that is attached to the top of the hinge post 5. One arm of the lever 25 extends slidably through the upwardly extending central portion of the walking beam or transverse lever 21, and the opposite end of the lever 25 is connected 30 to a pair of oppositely extending links 30 and 31. One of these links as 30 is supported at its outer end in the concaved or seat forming portion 12^a of one of the posts 12 and as in Figs. 1 and 2, and the remote end 35 of the link 30 may be provided with a grip or handle portion 30^a to be conveniently grasped by the occupant of a vehicle driving along the roadway R in the direction of the arrow a in Fig. 1, so that when the rod 30 is 40 pulled it sweeps the lever 25 in a horizontal direction and in an arc indicated by the arrow in Fig. 2 with the result, first that the walking beam or lever 25 is tilted on its fulcrum and one of the lifting hooks 17 is elevated and carries upwardly with it the adjacent end of the bolt 11 the opposite end of which is lowered from engagement with the yielding latches 7-7; and secondly a further pull on the operating link 30 causes 45 the gate to be swung on its hinges 4-4 to the fully open position shown in Fig. 2 where the outer end of the bolt 11 engages and is retained by the respective latch 13 on the remote post 12.

50 Having passed through the opened passageway the occupant of the vehicle can then grasp the handle of the actuating link 31, Fig. 2, and by pulling on the same will effect, first the tilting of the walking beam 21 on its 55 fulcrum so that one of the rods 17 will lift

the adjacent end of the bolt 16 and the opposite end will be disengaged from the latch 13, Fig. 2. Further pulling on the link 31 will sweep the lever 25 about its pivot to bring the gate 2 to the transverse position across 70 the roadway whereupon the bolt 11 will sweep beneath the near one of the yielding latches 7 and the same will lift sufficiently to permit the end of the bolt to pass into position between the inner ends of the latch 75 members 7, and thus the gate will be retained in closed position until the releasing and actuating mechanism is subsequently manipulated.

It is obvious that the device can be opened 80 in either direction by following the above described steps according to the direction of the occupant of the vehicle along the roadway.

Various changes may be made without departing from the spirit of my invention as 85 claimed.

I claim:

1. The combination with a pair of posts, of a gate hinged to one of the posts, a pair 90 of coöperating latches on the opposite post, a latch lever fulcrumed on the gate one end of which lever is adapted to be engaged by the latches, a horizontally disposed lever fulcrumed on the top of the post to which the gate is hinged, a transversely disposed member mounted for rocking movement on the top of the gate and to which the inner end of the fulcrumed lever is connected, rods depending from the ends of said rocking member, the lower ends of which rods engage beneath the inner end of the latch lever, guides on the gate for said rods, and operating rods connected to the outer ends of the fulcrumed lever and extending substantial 95 distances away from the gate in both directions.

2. The combination with a swinging gate of a hinge post and a latch post opposed upwardly yielding latches coöperative to retain the gate in a closed position, a latch lever pivotally mounted on the gate having a weighted inner end, its outer end adapted to engage the latches on the latch post, means to actuate said gate and said latch lever to 100 release the gate and pull it open in either direction, said means comprising a lever fulcrumed on the hinge post and having one end engaging a walking-beam pivotally mounted on the gate, to rock it in either direction, 105 said walking beam having downwardly extending rods on its outer ends adapted to lift the inner end of the latch lever against its weight, the opposite end of said lever pivotally connected to oppositely extending actuating links.

In testimony whereof I have signed my name to this specification.

WILLIAM F. GATEWOOD.
